Primary Examiner — Cynthia Underwood(74) *Attorney, Agent, or Firm* — David H. Jaffer; Pillsbury Winthrop Shaw Pittman LLP(57) **CLAIM**

The ornamental design for an display screen or portion thereof with animated graphical user interface showing an electronic PIN screen, as shown and described.

DESCRIPTION

FIG. 1 is a front view of a display screen or portion thereof with animated graphical user interface showing an electronic PIN screen showing a first image in a sequence of our new design; and,

FIG. 2 is a second image thereof illustrating s different state of entry of a PIN code.

The subject matter in this patent includes a process or period in which an image changes into another image. This process or period forms no part of the claimed design.

The dot dash dot broken lines represent a Display Screen and form no part of the claim.
